UNITED STATES PATENT OFFICE.

THOMAS J. CAHILL. OF PHILADELPHIA, PENNSYLVANIA.

COVERING.

1,357,541.

Specification of Letters Patent.

Patented Nov. 2, 1920.

Application filed August 13, 1919. Serial No. 317,369.

To all whom it may concern:

Be it known that I, THOMAS J. CAHILL, a citizen of the United States, and a resident of Philadelphia, in the county of Philadelphia and State of Pennsylvania, have invented a new and useful Covering, of which the following is a full, clear, and exact description.

This invention relates to a wing covering, 10 more particularly adapted for airplanes, which will render a tearing of such covering extremely difficult.

It is well known that when a small rupture occurs in the covering for the wings of 15 an airplane the velocity of the machine through the air causes this rupture to increase to such an extent as to disable the machine, very often resulting in the death of the occupants as well as the total destruction 20 of the machine.

In view of the foregoing, I have, as aforesigned, designed a covering for the wings of flying machines, and this covering could also be used as an envelop for the ballonnets 25 of a dirigible, and by means of which any hole or tear which might occur in such covering would be prevented from spreading, by confining this tear to a limited area. This strengthening of the covering would 30 not be a temporary one, but would also serve to prevent the spreading of a rupture even although the machine were traveling at great speed against a proportionate amount of air resistance.

35 Reference is had to the attached sheet of drawings which illustrates one practical embodiment of my invention, and in which—

Figure 1 illustrates one method of reinforcing the material covering the wings of 40 an airplane; and

Fig. 2 illustrates a modified form thereof.

In these views like reference characters indicate similar parts, and the reference numeral 1 designates the covering enveloping 45 the wings of an airplane, such covering being of silk, linen, etc. In this covering, reference being had particularly to Fig. 1, I

arrange lines of stitching running at an angle to the weave of the covering, as indicated at 2.

This stitching is preferably so arranged as to produce diagonal squares, which may be of a size proportionate to the size of the covering, and it will readily be appreciated that any rupture commencing at any point 55 in the covering would be restrained from spreading by means of such rows of stitching.

Referring now more particularly to Fig. 2, it will be seen that I have arranged the 60 stitching in this instance in the form of circles 3. By this arrangement of stitching the stretching of the material when being applied to an airplane wing is not in the least interfered with, and puckering is eliminated. It will be appreciated that in view 65 of the fact that the weave of the goods covering the wing in this instance would result in a tear running approximately length- or crosswise to the wing, by virtue of the 70 staggered relation of the circles of stitching one with respect to the other, any tear beginning in such covering will be immediately restrained from spreading.

The value of this invention may be well 75 appreciated in view of the fact that the same would not only prevent the spreading of ruptures in the covering but would also prevent the initial breakage of the covering in the event of an airplane landing upon 80 rough water, which usually results in the cover upon the underside of the wing being badly mutilated.

It will be further understood that any 85 number of arrangements of stitching might be utilized without in the least departing from the scope of my invention.

Having thus described my invention, I desire to claim:

A covering for flying machines, including 90 a woven material, and rows of stitching in said material extending at an angle to the weave of the same.

THOMAS J. CAHILL.
